ADJUSTABLE CHAIR

Kenneth K. Kissell, Cleveland, Ohio, assignor to
Eula Elizabeth Esping

Application March 9, 1945, Serial No. 581,748

1 Claim. (Cl. 155—106)

1

This invention relates to improvements in that class of chairs especially intended for invalids' or convalescents' use, and among the objects of my invention are to provide a chair of this class that is extremely comfortable in that the weight of the user is supported entirely by a flexible web so that his body is out of contact with any hard object; to provide a chair of the aforesaid class that can readily be adjusted between an upright sitting position and a fully reclining position simply by the occupant changing his posture; to provide a chair of the nature just mentioned that is well balanced in all positions and tends to retain its various positions of adjustment by reason of the manner in which the weight of the occupant is distributed; to provide in a chair of this character means in convenient reach of the occupant and readily manipulated by him for readily retaining the adjustable structure in any position to which it is adjusted, and to provide a chair of the invalid class including the usual wheels and trailing casters and from which said wheels and casters may be readily removed so as to convert the chair into one of the standing type for more general use as on a porch or lawn.

Other objects and advantages will appear as I proceed to describe the invention in detail by reference to the accompanying drawing, and among which are the more general ones of simplicity of design and construction, economy, strength and durability.

In the drawing, wherein like reference characters designate corresponding parts throughout the several views, Fig. 1 represents a front elevation, and Fig. 2 a side elevation of a chair constructed in accordance with my invention; Fig. 3 is a vertical section from front to rear through the chair, showing it adjusted to an almost fully reclining position; Fig. 4 is an enlarged sectional detail through the edge portion of the seat, as indicated by the line 4—4 of Fig. 2; Fig. 5 is an enlarged detail of one of the trailing casters, and Fig. 6 a sectional detail showing a supporting stay for the rear portion of the seat.

The chair comprises, generally, a rigid supporting frame, and an adjustable structure made up of back, seat and front sections, and which structure is pivotally connected to and sustained by the supporting frame. The supporting frame, according to the present embodiment of the invention, is built up of two X-shaped parts 1, desirably fabricated of metal tubing, that are connected together adjacent their lower ends by a horizontal member 2 which extends across the back and forwardly along each side and is con-

2

nected to the lower portions of said X-shaped parts 1, said parts also being rigidly connected together adjacent their lower front corners by a cross bar 3. The supporting frame is desirably fitted with casters 4 of the size ordinarily employed on pieces of furniture, and said frame is further braced by a cross member 5 that extends between the downwardly and rearwardly inclined members of the X-shaped parts. The supporting frame is completed by substantially horizontal, parallel side members 6, shown as including armrests 7.

Unless the structure is to be used as a standing chair, in which case it would rest on the casters 4, it is provided with relatively large wheels 8 and trailing casters 9. The trailing casters are of conventional construction and are removably connected to the rear portion of the member 2 in any suitable manner obvious to the average mechanic. The axis 15, on which the wheels 8 are mounted, is removably supported by brackets 16 by being withdrawable therefrom, said brackets being connected to the forwardly and downwardly inclined members of the parts 1.

The back, seat, and front sections of the above mentioned adjustable structure are designated, generally, by the reference numerals 20, 21 and 22, respectively. The back section 20 is made up of side rails 23, that are connected together at their upper ends by a cross bar 24, and at their lower ends by a cross bar 25. Intermediate their ends, the side rails 23 have hangers 26 secured to them, and said hangers are connected by pivot members 27, to the rear end portions of the side members 6 of the supporting frame. Pivotally connected to the front ends of said side members are the side rails 28 of the front section 22; and near their lower ends said rails 28 are rigidly connected by a cross bar 29. Pivoted at 30 to brackets 31 that are secured to and extend rearwardly from the side rails 28 of the front section are the forward ends of side rails 32 of the seat section 21. The side rails 32 extend rearwardly beyond, and inside those of the back section and are pivotally connected to the side rails of the back section by bolts 33, said bolts, according to the present embodiment, also assisting in holding clamping strips 34 to the inner sides of the rails 32. The lateral edges of a cross web 35 of suitable flexible material, such as a relatively heavy and strong grade of carpet, are firmly clamped between the strips 34 and the rails 32, a suitable number of bolts 36, additional to the bolts 33, being employed for firmly securing the parts together. Adjacent the front of the seat

section, the sides thereof may be held apart by a drop-yoke 37. It will be noted from Figs. 2 and 3 that the seat section projects a material distance rearwardly of the back section, and that the cross web 35 extends from the rear end of said section entirely to the front thereof. To prevent the side rails of the seat section, along with the clamping strips 34, from keeling over under weight imposed upon the cross web 35 when the chair is in use, the inner ends of the bolts 33 have connected to them, and are sustained by, stays 38 that have a purchase at their lower ends on the cross bar 25 of the back section 20. The connection between the inner ends of the bolts 33 and the stays 38 may be conveniently made by threading the bolts into tapped holes in the stays, in a manner obvious to one skilled in the art.

A longitudinal web 40 of flexible material, such as a heavy grade of canvas, is secured at one end to the upper cross bar 24 of the back section 20 and at its opposite end to the cross bar 29 of the front section 22, said web overlying the cross web 35, the latter desirably being stretched tightly between the sides of the seat section 21. A footrest 42 is pivotally supported by and between the lower ends of the side rails 23 of the front section 22 and is releasably held in a position at substantially right angles to the plane of said section by braces 44 that are detachably connected at their upper ends to the side rails 23.

Constructed as above described, the adjustable structure is capable of swinging with a sort of parallel rule action between a position in which the back and front sections are approximately vertical, as shown in Fig. 2, and one in which said sections closely approach a horizontal position, the seat section at all times remaining substantially horizontal; and it is evident from the construction described that a person occupying the chair is at all times supported from his head to the region of his feet by the webs of flexible material and entirely out of contact with any rigid part of the structure, it being explained that the top cross bar 24 of the back section is well above the head of a person of average height when seated in the chair. By extending the seat section a considerable distance rearwardly of the back section, the body is well supported when in a reclining position; and when in such position, the occupant of the chair may disengage the braces 44 of the footrest and swing the latter downwardly into the plane of the front frame, where it is held by engagement with the covered cross bar 29, so as to more comfortably support the feet.

A slotted plate 46 is pivoted at 47 to one of the side members 6 of the supporting frame, and

projecting through the slot thereof is a threaded stud 48 on the adjacent side rail 23 of the back section. By means of a thumb nut applied to said stud, the plate may be locked to said rail so as to firmly hold the adjustable structure in any desired position.

Having thus described my invention, what I claim is:

In a chair of the class described, the combination of a supporting frame, and an adjustable structure sustained thereby comprising a back section, a seat section and a front section, the back and front sections being pivotally connected to the supporting frame, and the seat section being pivotally connected at its forward end to the front section and adjacent its rear end to the back section, the seat section projecting a considerable distance rearwardly of its connection with the back section, said seat section comprising side rails and a rigid cross member connecting them together adjacent their forward ends, said member being spaced a substantial distance below the plane of the top edges of the side rails, a cross web of flexible material having its lateral edges secured to the side rails of the seat section along their top edges and extending from the front to the rear thereof, said cross web being sufficiently taut to remain out of contact with the aforesaid cross member under the weight of a person occupying the seat, and a longitudinal web of flexible material attached at one end to the top of the back section and overlying the cross web and secured at its opposite end to the lower portion of the front section, the longitudinal web being supported intermediate its ends solely by the cross web and being freely movable with relation thereto.

KENNETH K. KISSELL.
